UNITED STATES PATENT OFFICE.

RALPH C. BROWNE, OF SALEM, MASSACHUSETTS.

TELEPHONE RECEIVER.

Application filed September 9, 1922. Serial No. 587,124.

To all whom it may concern:

Be it known that I, RALPH C. BROWNE, citizen of the United States, residing at Salem, in the county of Essex and State of Massachusetts, have invented certain new and useful Improvements in Telephone Receivers, of which the following is a specification.

This invention relates to telephone receivers and more particularly to what is known as loud speakers or amplifying receivers especially adapted for use with radio.

One of the objects of the present invention is to provide an instrument of the above character that will produce tones true in character and of great volume.

A further object is to provide an apparatus of the above character having relatively few parts which may be inexpensively manufactured and assembled.

A further object is to provide a light, compact and self-contained apparatus or device adapted to be used with commercial radio sets now on the market for amplifying and reproducing sounds in a clear and distinct manner.

A further object is to provide a device of the above character with adjustments whereby it may be tuned to respond to one particular frequency, thereby enabling the spark signals to be read through strong "static."

Other objects will be in part obvious and in part hereinafter pointed out.

The invention accordingly consists in the features of construction, combination and arrangement of parts, and in the unique relation of the members and of the relative proportioning and disposition thereof, all as more completely hereinafter outlined.

To enable others skilled in the art to fully understand and comprehend the underlying features of this invention, and in order that they may embody the same by numerous modifications in structure and relation contemplated by this invention, drawings depicting several desired forms have been annexed and made part of this disclosure and in such drawings like reference characters denote corresponding parts throughout all the views, in which—

Figure 1 is a semi-diagrammatic sectional plan view showing the essential circuits and arrangement of the component parts utilized in the invention in its simplest form;

Figure 2 is a similar view showing a slight modification in the method of attaching the diaphragm to the vibrating member;

Figure 3 is an elevational view taken substantially on the line 3—3 of Figure 1; 60

Figure 4 is a detail view illustrating the shape of the conducting and vibrating member attached to the diaphragm;

Figure 5 is a sectional perspective view of an ear receiver; 65

Figure 6 is a view similar to Figure 1 with a transformer attachment shown diagrammatically; and

Figure 7 is a view similar to Figure 1, showing the method of tuning the vibrating member. 70

In order that a clearer conception of the present invention may be had and the objects sought to be accomplished, it may be stated that instruments of this character heretofore have comprised a coil of wire adapted to receive a telephonic current, said coil being adapted to vary the magnetic pull on a diaphragm as in the ordinary receiver or be itself connected with a suitable diaphragm and thereby transmit to it vibrations brought about by reason of the reaction between currents traversing it and an associated field of magnetic force. Either of the classes referred to have certain defects. In the first case, the diaphragm is at all times subjected to a magnetic pull and is thereby under tension which is objectionable, and in the second case, the coil and its necessary support add undesirable weight to the diaphragm. Other arrangements have been suggested based upon the polarized type of relay, but these arrangements have had an even more serious drawback in the introduction of pivoted levers and mechanism that tends to rattle and produce false tones. 80 85 90 95

All of the above defects are overcome in the present invention and results are attained in a class by themselves. Moreover, if desired the present device may be mechanically tuned to respond to one particular frequency and thereby becomes particularly efficient in recording spark signals in wireless telegraphy, thereby enabling the signals to be read under most adverse "static" conditions. 100 105

Referring now to the drawings in detail, and more particularly to Figure 1, 10 denotes a base member of any desired type 110

upon which are mounted the poles N and S, of a magnet 11. In practice, it is preferred to utilize an electrolyte, as shown, although permanent magnets have been found to give 5 excellent results and are recommended in certain types of apparatus hereinafter described. Between poles N and S of the magnet there is provided a conductor 12 of preferably solid metal and in the form of an 10 aluminum wire, although I do not limit myself to the particular shape or material. This conductor 12 is attached at one end to a fixed clamp 13 insulated from the rest of the mechanism by means of block 14. The 15 opposite end is rigidly attached to a diaphragm 15 mounted in a suitable support 16 secured, as by means of fastening devices 17, to the poles N and S. With this arrangement I find that a telephone current entering through leads 18 and 20 and allowed to traverse the conductor 12 will cause the same to be thrown into vibration in synchronism 20 with the polarization or wave of the telephone current. The vibrations occurring in the conductors 12 have two components, that is, transverse and longitudinal. The longitudinal vibrations are utilized in moving the diaphragm 15 to which it is attached. It 25 will be noted that the movement of the diaphragm and the movement of the vibration utilized in the conductor 12 is in the same direction as the flow of current through the conductor. This type of apparatus represents the simplest arrangement and it will 30 be noted that the moving parts in addition to the diaphragm are extremely light especially when aluminum is used for the conductor.

In actual operation of the device, excellent 40 results have been obtained by using the arrangement shown in Figure 2. In this case instead of directly connecting the end of the conductor 12 to the diaphragm 15 I prefer to connect one end of the conductor 45 12 to a lever 21 pivoted at 22, the opposite end of which lever is connected to the center of the diaphragm as shown. This construction is similar to that utilized in the manufacture of sound boxes or phonographs, as 50 is well known in the art pertaining to such apparatus. One of the objections of this construction is to do away with any lateral displacement of the conductor 12 being imparted to the diaphragm and also to control 55 the amplitude of movement. The conductor 12, as shown in Figure 4, is not in practice stretched tightly between the clamp 13 and the diaphragm 15, but preferably has a slight bend, as indicated and is without tension. This enables the conductor to vibrate 60 uniformly with the wave of the telephonic current and also frees the diaphragm from any undesirable tension. In special cases where it is desired to tune for one particular

tone frequency the conductor 12 may be 65 stretched tightly and, in fact, tuned by so doing, as shown in Figure 7, in which case the clamp is replaced by a thumb screw 23, which will allow any desired tension to be placed upon the conductor 12, this thumb 70 screw being mounted in a bracket 24 secured to, but insulated from the pole pieces N and S.

In order to obtain the highest efficiency, an apparatus such as illustrated in Figure 6 75 may be used, wherein there is indicated between the leads 18 and 20 a transformer 24. This is especially desirable if the telephonic current has a comparatively high voltage and low amperage, and it is desired to change its characteristics, thereby producing a current of comparatively high amperage and low voltage through the conductor 12. The member 16 is provided with a nipple 25 to which an amplifying horn may be conveniently attached. 80

If desired the size of the component parts of the system herein illustrated and described may be reduced and readily installed in an ordinary watch case head receiver, as 90 shown in Figure 5. In this case there is employed a permanent magnet 26 having poles N and S and between these poles there is placed the conductor 12 in contact at one end with the diaphragm 15 and at the opposite end clamped by any suitable means to the back of the case 27, the other part of the case 28 being screwed thereto in the usual manner. The essential parts of the mechanism are substantially the same in construction and operation as above described. This, however, permits one to make the diaphragm 95 100 105 110 115 120 125 130 135 140 145 150 155 160 165 170 175 180 185 190 195 200 205 210 215 220 225 230 235 240 245 250 255 260 265 270 275 280 - acteristics within said field and a diaphragm, connected with said conductor, said parts being so related that a telephonic current passing through said conductor will cut the 5 lines of force of the field thereby to set up a moving force in said conductor to vibrate said connected diaphragm.
2. A telephone receiver comprising pole pieces having a magnetic field therebetween, 10 a semi-rigid conductor passing through said field, a diaphragm connected to said conductor, and means whereby a telephonic current passing through said conductor will cause said conductor to exert a moving force 15 on said diaphragm to thereby vibrate the same, the vibrations of said diaphragm being synchronous with the operating current flowing through said conductor.
3. A telephone receiver comprising pole pieces having a magnetic field therebetween, 20 and a conductor extending through said field, one end of said conductor being positively clamped, the opposite end of said conductor being mechanically connected to 25 said diaphragm, whereby vibration of said conductor is transmitted to the diaphragm at one end thereof.
4. A telephone receiver comprising a dia- 30 phragm, a bent conductor having one end connected to said diaphragm, pole pieces adapted to produce a magnetic field there- 35 between said conductor being positioned in said field, and a clamp for holding the opposite end of said conductor.
5. A telephone receiver comprising a dia- 40 phragm, a conductor attached to said dia- phragm, a clamping member for said con- 45 ductor, and a pole piece having magnetic field therebetween said conductor being positioned in said field, said magnetic field being so related to said conductor that a telephonic current passing through said conductor will act to alternately push and pull the dia- 50 phragm to thereby vibrate the same.
6. A telephone receiver comprising pole pieces having a magnetic field therebetween, 55 a substantially rigid conductor within said field, one end of said conductor being fixed to a diaphragm connected with the other end of said conductor whereby a telephonic current passing through said conductor will vibrate said diaphragm by vibrations set up in said conductor.
7. A telephone receiver comprising pole 60 pieces having a magnetic field therebetween, a single conducting rod in said field, a dia- phragm connected therewith, whereby as the telephonic current passes through said conducting rod and imparts a moving force thereto the diaphragm will be vibrated.
8. A telephone receiver comprising pole 65 pieces having a magnetic field therebetween, a single conductor within said field, a dia- phragm mechanically connected with said
- conductor, whereby the diaphragm will 65 vibrate as the current passes through said conductor, said conductor comprising a slightly curved rod securely held at one end and attached to the diaphragm at its other 70 end.
9. A telephone receiver comprising pole pieces having a magnetic field therebetween, 75 a single conductor within said field and a diaphragm mechanically connected with said conductor, whereby the diaphragm will vibrate as the current passes through said conductor, said conductor comprising a slightly curved semi-rigid wire securely held at one end and attached to the diaphragm at its other end, and means for varying the 80 curvature of said wire.
10. A telephone receiver comprising a base, a permanent magnet associated with 85 said base, a single conductor extending through the field of said magnet between its poles, and a diaphragm to which the other end of said armature is connected, whereby as a telephonic current passing through said conductor will cause said conductor to exert a moving force on said dia- 90 phragm, synchronous with the fluctuations of said telephonic current, said moving force being inherent to the electric current and to said conductor.
11. A telephone receiver comprising a 95 base, a magnet mounted on said base, a con- ductor positioned transversely in the field of said magnet, a clamping member hold- 100 ing one end of said conductor, a diaphragm secured to the opposite end of said conductor, the magnetic field surrounding said conductor being so related thereto that a current passing through said conductor will result in the vibration thereof, said con- 105 ductor when vibrated adapted to inherently impart a moving force to said diaphragm synchronous with the fluctuations of the current passing through said conductor.
12. A telephone receiver comprising a 110 base, coils mounted on said base, magnetic core members of rectangular shape associated with said coils for creating a mag- 115 netic field, a conducting rod transversely disposed in said field, a clamping member for one end of said wire, a diaphragm to which the other end of said conducting rod is connected, and means for regulating the tension on said conducting rod, said parts being so positioned that a current passing 120 through said conductor will cause the same to vibrate and to inherently impart vibra- 125 tions to the diaphragm positioned at one end thereof.
13. A telephone receiver comprising pole pieces having a magnetic field therebetween, 125 an aluminum wire mounted in said field, and a diaphragm connected to one end of said wire said aluminum wire adapted to in-

herently impart a moving force to said diaphragm when a telephonic current is passed through said wire.

14. A telephone receiver comprising pole pieces having a magnetic field therebetween, an aluminum wire mounted in said field, and a diaphragm connected to one end of said

wire, the other end of said wire being fixed, said aluminum wire adapted to inherently impart a moving force to said diaphragm ¹⁰ when a telephonic current is passed through said wire.

In testimony whereof I affix my signature.

RALPH C. BROWNE.
